UNITED STATES PATENT OFFICE

ALBERT M. GUILLET, OF CHARLOTTE, NORTH CAROLINA

INTERCHANGEABLE JOURNAL FOR TEXTILE ROLLS

Application filed July 11, 1929. Serial No. 377,398.

This invention relates to spinning machinery and more particularly to a method of joining adjacent fluted rolls together so as to cause the rolls to function as good if not better than new rolls, and my invention is 5 adapted to be used in the manufacture of new rolls as well as in the repair of old rolls.

The front rolls of spinning machines which carry fluted bosses are usually made in sections, each section carrying upon it a plurality of fluted bosses and the sections being joined by a neck which forms a journal bearing for the series of rolls and which is formed beyond the journal bearing with a male square 15 end adapted to fit within a female square or many-sided socket formed in the adjacent end of the next adjacent roll section. Each of these necks, as before remarked, is provided with a journal bearing rotating within a 20 roll stand, and when the journal bearing of a section becomes worn it is necessary that it shall be renecked, which means that the section must be removed from the roll stand, sent to a machine shop, the neck must be 25 sawed off adjacent the junction of the journal portion with the body of the section, then the end of the body-section must be bored out, and a new neck having a journal portion thereon and a squared portion must be driven 30 into this bore until a driving fit is secured. This is a more or less expensive operation and it is not very satisfactory for the reason that it is difficult to get a perfect drive fit between the new neck and the body of the section 35 and one that will not permit the neck to become loose. Also by driving the new neck into the end of the old roll, if a driving fit is secured there is a tendency to swell the ends of the roll and therefore cause the ends of the 40 roll to be larger than the other portion of the roll.

The general object of my invention is to provide an interchangeable journal with a combination of a screw and a taper fit for 45 fluted textile rolls, which journal may be readily inserted into the extremity of the roll sections and removed if necessary, it being an object of my invention to provide a very strong replacement part for joining the sections of rolls and one that will not become

broken, and also one which will not interfere with the size of the rolls as there is no driving and swelling of the end portions of the rolls.

Another object of my invention is to provide an interchangeable journal for textile rolls which comprises an elongated portion of the same size as the journal portion is adapted to fit into elongated bores in the end of the rolls with a tapering bottom to the innermost end of the bores and with a smaller bore extending from the bottom of each of the larger bores, with said smaller bores being threaded and with a journal portion adapted to extend into the large bores with a tapered slope to the said journal portion, and with the ends of the journal portions being threaded so that I not only obtain a screw fit with straight threads thereon and with a tapered portion as is set forth in my Patent, Number 1,659,261 of February 14, 1928, but I also secure additional reinforcement for the junction point of the journal and the roll by having the journal extend into the end of the roll for some distance without diminishing in size.

A still further object of my invention is to provide an interchangeable journal for joining rolls together with both ends of the journal being alike and thus causing it to be interchangeable under all conditions.

Some of the objects of my invention having been stated other objects will appear as the description proceeds, when taken in connection with the accompanying drawings, in which—

Figure 1 is a side elevation mostly in cross-section showing my invention;

Figure 2 is a view showing one end of a roll in cross-section after being bored out and threaded to fit my interchangeable journal;

In rolls which are manufactured and placed on spinning machinery the predominating structure has a journal made integral with one roll which journal portion is squared and this squared portion is adapted to be fitted into a square hole in the end of another roll section, and as pointed out in my objects of invention it has heretofore been necessary in replacing the worn-out portion to saw off the

neck from the roll and drill out the end of the roll and insert a new journal which is driven in the end of the roll.

My invention can be applied to old rolls of this character or to new rolls, and in either case my invention is described best by stating that the rolls 10 and 11 are first bored at the end portions thereof by the cavity 12, and then the smaller bore 13 is bored in the bottom of the bore 12, and then a reamer is placed in the bore 12 which reams out the sloping shoulder portion 14 and then the interior of the bore 13 is threaded.

I then provide the journal portion or neck 15 which is adapted to fit into the bores 12 and 13, this journal portion 15 having the sloping shoulder portion 16 and the threaded portion 17 on either end thereof. It is thus seen that the elongated portion of the neck 15 which extends into the large bore 12 forms a very strong structure and this is necessary due to the fact that between each of the fluted rolls as at the point 18 weights are placed, and this causes a good bit of strength to appear between the journal portion 15 in each of the rolls, but having the elongated bore 12 into which the journal or neck 15 fits without diminishing in size, I provide an additional reinforcement and a more substantial structure than that set forth in my Patent Number 1,659,261 of February 14, 1928 which is similar to the structure herein described with the exception that the elongated bore 12 is not present.

In applying my invention to old rolls it is only necessary to cut off the journal and then bore out the cavities 12 and 13 and form the sloping shoulder 14 and then form the threads in the cavity 13 and then take the other roll and bore out the squared cavity similar to the cavity 12, and then bore the cavity 13 in the bottom thereof with the sloping shoulder 14, and thus we have both ends of both rolls similar so that my interchangeable journal 15 can be inserted therein and screwed in position with the sloping portion 16 on the member 15 and fitting snugly against the shoulder 14 and the threaded ends 15 fitting snugly to the threaded portion 13 in each of the rolls. It is thus seen that I have provided a very substantial structure, which is adaptable to old and new rolls, and which forms an interchangeable journal which can be removed and the new member 15 inserted therein from time to time without the necessity of sending the rolls to a machine shop, as all that will be necessary is to reinsert a new member 15 when the old member 15 becomes worn out.

In the drawings and specification I have set forth a preferred embodiment of my invention, and although specific terms are employed, they are used in a generic and descriptive sense only, and not for purposes of limitation, the scope of the invention being set forth in the appended claims.

I claim—

1. A roll for textile machinery comprising an extended bore in each end of the roll, a smaller bore in the central portion of the first named bore, and extending further into the roll, the smaller bore being threaded, a sloping portion between the smaller and larger bores and a journal member adapted to fit into the large and small bores, the end of the journal member being threaded to threadably engage the threads in the smaller bore, said journal having a tapered portion adapted to fit against the sloping portion joining the larger and smaller bores. 70

2. A textile roll having an elongated bore 80 in the end thereof, a smaller bore extending from the base of the large bore further into the roll, the smaller bore being threaded, a sloping portion joining the smaller and larger bores, and a journal member adapted to fit 85 into the large and small bores with the portion fitting into the small bore being threaded to threadably engage the small bore, and a sloping portion on said journal adapted to fit against the sloping portion of said bore. 90

3. In a connecting member and journal for joining sections of textile rolls, a bore in each end of the textile rolls, a smaller bore in the base of each of said larger bores, a sloping shoulder portion joining the larger and smaller bores, a journal member having the journal portion of the same diameter as the portion which is adapted to fit into the larger bore, a sloping shoulder portion on said journal portion adapted to fit against the sloping portion 100 in said bore, a threaded portion on the end of said journal adapted to fit into the threaded portion or smaller portion of said bore, the end of said threaded portion being adapted to fit flush against the bottom of said smaller bore and the tapered portion on said journal being adapted to fit flush against the tapered shoulder portion in said bore to form a snug fit between the larger and smaller bores and the tapered portion and the journal fitting therein. 105

4. A roller neck for joining sections of textile rolls together comprising a bearing portion extending into the rolls with a tapered shoulder at each end of the bearing portions, 115 said rolls having bores adapted to fit said portions of the roller neck snugly at all points on the portions of said roller neck.

5. The combination with two spinning 120 rolls, of a relatively short journal member disposed between two rolls and locking the two rolls together for unitary rotative movement, said journal member having a middle journalled portion extending into the ends of proximate rolls, a sloping shoulder portion, a smaller threaded portion extending from said sloping portion, the proximate ends of said rolls having bores adapted to fit the above mentioned portions of the end portions, 125 130

the smaller bore being threaded to engage the threaded ends of the journal member whereby the sloping shoulder portion of the journal is caused to fit against the sloping shoulder in the bore in said rolls to limit relative movement between the journal and the rolls and to prevent swelling of the ends of the rolls by said journal member.

6. Means for joining sections of textile rolls together comprising a roller neck having a bearing portion and portions on each side of said bearing portion of the same size as the bearing portion extending into bores in the proximate ends of two rolls, each of said rolls having a tapered bore, extending from the base of the first bore and also having a threaded bore extending from the base of the tapered bore, said journal having a tapered portion adapted to fit against said tapered bore, and also having a threaded portion adapted to be driven home in the threaded bore to cause the tapered portion on the journal to fit snugly in said tapered bore.

7. The combination of two textile rolls and a roller neck for joining the rolls together, the proximate ends of the rolls having elongated bores extending thereinto, with a tapered bore extending from the base of each bore further into the rolls and a threaded bore extending from the base of the tapered bores further into the rolls, a journal member having a bearing portion with other portions adjacent thereto extending into the said bores, a tapered portion on said journal member adapted to fit against the sidewalls of said tapered bore when driven home, and a threaded portion adapted to be driven home in said threaded bores, the tapered bore and tapered portion on the roller neck limiting relative movement between the roller neck and the roll and also preventing swelling of the roll by said roller neck.

In testimony whereof I affix my signature.
ALBERT M. GUILLET.
